UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,141,558.

Specification of Letters Patent.

Patented June 1, 1915.

Application filed July 23, 1910. Serial No. 573,407.

To all whom it may concern:

Be it known that I, ALFRED G. F. KUROWSKI, a citizen of the United States, residing in the borough of Brooklyn, city of New York, in the county of Kings and State of New York, have invented certain new and useful Improvements in Type-Writing Machines, of which the following is a specification.

This invention relates to paper feeding devices for typewriting machines, and particularly to means whereby envelopes, bill heads or other work sheets are fed or moved in line-spacing direction at one operation through a greater distance than is obtainable by the use of the regular line-spacing mechanism, to bring the first printing line thereon to the printing point of the machine.

According to the invention, by swinging a driver or crank, a pawl connected thereto is caused to drive a ratchet that is fast upon a comparatively large gear, said gear meshing with a comparatively small pinion, the latter being secured to the axle of the platen, whereby the platen is rotated through a longer arc than is traversed by the crank or driver. The platen has the usual line-space mechanism including a notched line-space wheel engaged by a detent.

To facilitate the turning of the platen and reduce the noise of operation, the usual spring detent engaging the line-space wheel is silenced during the initial or driving stroke of the crank or lever, by a cam lever rocked by a cam controlled by the crank. The detent is caused to reseat itself directly in a notch in the line-space wheel, without turning the latter, when the platen is arrested at the end of its rotation.

In the accompanying drawings, Figure 1 is a perspective view, showing one form of the invention applied to the platen frame of an Underwood writing machine. Fig. 2 is a side view, partly broken away. Fig. 3 is a similar view, parts being removed, the driving lever being in normal position. Fig. 4 shows the driving lever partly advanced, and the pawl in engagement with the ratchet. Fig. 5 shows the positions of the parts at the end of the initial stroke of the driving lever. Fig. 6 is an edge view, partly in section.

The usual platen 1 is mounted on an axle 2 journaled in platen frame ends 3, and manually rotated to an unlimited extent forwardly or backwardly by finger wheels 4 on

said axle. The platen may also be rotated forwardly by the usual line space mechanism, comprising a lever 5 pivoted to the main carriage at 6 to operate a slide 7 having a pawl 8 to engage a notch line-space wheel 9 fast on the platen axle 2. A spring-pressed detent 10 engages said line-space wheel, and is releasable by a cam lever 10^a hung on the axle 2, as usual.

The gross line-spacing mechanism is mounted preferably at the same platen end with the regular line-space mechanism, and comprises a driving lever or crank 11 journaled on a stud 12 mounted on the platen frame end 3, to turn the platen, and swinging in an arc above the platen, to be operable at any point in the travel of the carriage without obstruction by other parts of the machine. The lever is normally held by a returning spring 18 against a rest 17.

The initial or driving stroke of the lever or crank 11 from its position in Figs. 2 and 3, in the direction of the arrow, first causes a pawl 13, pivoted to the lever at 13^a, to ride off a switch or trip 20, whereupon the spring 18 acts to effect the immediate engagement of the pawl with a ratchet 14 (Fig. 4). Said trip 20 lies substantially concentric with ratchet 14, and supports the pawl out of contact with the ratchet, to enable the platen 1 to be turned freely in either direction independently of the gross line-spacing mechanism. Continued forward movement of the lever 11 rotates the ratchet to turn a gear 15 fast therewith, said gear being journaled on the stud 12 and meshing with a smaller pinion 16, the latter fast on the axle 2 of the platen, to turn the latter. The platen is thus advanced a great distance and until arrested by the engagement of the pawl with a stop 21, (Fig. 5).

Owing to the relative sizes of the gear and pinion, a partial rotation of the ratchet and gear will turn the platen through a comparatively long arc, to advance the first writing line of the work sheet to the printing point. Said stop projects from an arm 22, preferably secured to the stud 12, the stop being entered in any of a series of apertures 23 formed in the platen frame end 3 and constituting a rack which may be concentric with the ratchet, to enable the stop to be adjusted toward and from the switch or trip 20, to vary the throw of the driver and hence of the platen, whereby envelopes

and work sheets having different widths of top margins may be advanced to bring the first line thereon to the printing point. Said adjustment is obtained by removing the fastening screw 24, which secures the arm in place on the stud, adjusting the stop, and replacing the screw.

The pawl may have a lateral abutment 25 to engage the stop 21 at a point close to the support of the latter, to avoid straining the stop in case the driving lever 11 is forcibly operated. The abutment 25 and the stop 21 coöperate to lock the ratchet wheel 14 and the platen against overthrow, as will be understood from Fig. 5.

The hub 26 of said driving lever has a cam 27, which, when the driving lever is swung on its initial stroke, engages one end of a detent-releasing lever 28 pivoted at 29 (and preferably having an anti-friction roller 31 to run on the cam) to rock the latter and cause a cam 30 (at its opposite end) to crowd against a pin 32 on the detent 10, to release the latter from the line space wheel 9. This is done at the first portion of the initial stroke of the crank 11. It will be seen that the cam 27 has a long dwell portion concentric with axle 12, which maintains the detent in inoperative position during the turning of the platen by the driver, and eliminates the clicking noise that would be caused by the detent running over the teeth of the line-space wheel. Upon the release of the handle or driver, (Fig. 5), the spring 18 returns it to normal position (Fig. 1), the pawl 13 moving idly over the ratchet 14 and finally riding upon the trip or switch 20 out of contact therewith. Said returning spring may be coiled about the stud 12 and protected from injury by a shield 19. The return movement of the handle 11 also releases the rocking lever 28 from the hub cam 27, whereupon the detent 10 snaps into one of the notches of the line-space wheel.

The rotation of the platen and line-space wheel by the driver may be so controlled that, when the platen is arrested, a notch of the line-space wheel will register with the detent. The ratio between the pitch of the teeth on the line-space wheel 9 and that of ratchet 14 conforms to the ratio between the pitches of teeth on the pinion 16 and driving gear 15. Thus, if the ratio between the gear and pinion is as three to one, then the ratchet 14 has three times as many teeth as wheel 9, and hence the rotation of the crank 11 through one-third of the revolution would turn the platen through a full revolution. The stop 21 is located at a point to arrest the platen when detent 10 registers with a notch in wheel 9; and the openings 23 may be placed at intervals to agree with the pitch of teeth of ratchet 14, as shown in dotted circles at Fig. 3.

If there are thirty-three teeth on the line-space wheel and eleven teeth on the pinion 16, the gear will have thirty-three teeth, and there will be ninety-nine teeth on the ratchet. The advance of the ratchet through a space equal to one tooth, therefore, will turn the line-space wheel 9 through one whole tooth space.

Variations may be resorted to within the scope of the invention, and portions of the improvements may be used without others.

Having thus described my invention, I claim:

1. In a typewriting machine, the combination with a platen, and a line-space wheel and detent therefor, of a gross line-spacing mechanism including a train of gears connected with the platen, a pivotally supported crank having a pawl which, when the crank is rocked in one direction, operates the train of gears to advance the platen, means connected to said crank for releasing the detent, and means to lock the platen against overthrow when operated by said crank.

2. In a typewriting machine, the combination with a platen and a regular line-space mechanism therefor, of an auxiliary platen turning mechanism including a train of gears, one of which is connected with the platen, a pivotally supported driving mechanism to turn another of said gears to rotate the platen in one direction, and a switch engaged by the driving mechanism on its return stroke to hold it disengaged from the gear to permit the platen to be turned independently thereof in either direction.

3. In a typewriting machine, the combination with a platen, a regular line-space mechanism including a notched line-space wheel, and a detent for said wheel, of an auxiliary platen turning mechanism including a train of gears, one of which is connected to the platen, a pivotally-supported driver to operate the gears to turn the platen in one direction, a releasing lever operated by the driving mechanism to render the line-space wheel detent idle during the rotation of the platen when driven through the gearing, means to return the driving mechanism to original position, to enable the engagement of the detent with its line-space wheel, and a switch effective to hold the driving mechanism disengaged from the gearing to enable the platen to be turned in either direction independently thereof.

4. In a typewriting machine, the combination with a platen, a regular line-space mechanism including a notched line-space wheel, and a detent for said wheel, of an auxiliary platen turning mechanism comprising a pinion connected with the platen, a gear meshing with the pinion, a driving mechanism to operate the gear to turn the platen, and having a cam, a cam lever

rocked by the cam when the driving mechanism is operated in one direction, to disengage and hold the detent in idle position, and a switch normally maintaining the driving mechanism disconnected from the gear to enable the platen to be turned in either direction independently thereof.

5. In a typewriting machine, the combination with a platen frame, a platen, and a regular line-space mechanism therefor, of a pinion connected with the platen, a gear journaled on the platen frame and meshing with the pinion, a pivotally supported finger lever having a pawl, a ratchet turning with the gear and engaged by the pawl to turn the platen when the finger lever is swung in one direction, a stop in the path of the pawl and an offset abutment on the pawl to engage the stop near its point of support to avoid straining the stop, and means to disengage the pawl from operative position.

6. In a typewriting machine, the combination with a platen frame, a platen, and a regular line-space mechanism therefor, of a pinion connected with the platen, a gear journaled on the platen frame and meshing with the pinion, a pivotally supported finger lever having a pawl, a ratchet turning with the gear and engaged by the pawl to turn the platen when the finger lever is swung in one direction, a spring to cause the pawl to bite the ratchet and to return the finger lever to original position, and a switch over which the pawl rides on the return of the finger lever to disconnect the pawl from its ratchet.

7. In a typewriting machine, the combination with a platen frame, a platen, regular line-space mechanism, including a notched line-space wheel, and a detent engaging the wheel, of a pinion connected with the platen, a gear journaled on a stub shaft supported by the platen frame and meshing with the pinion, a driving lever having a hub pivoted on the shaft, a pawl on the driving lever to turn the gear and rotate the platen, a cam lever pivoted on the platen frame, a cam on the hub of the driving lever effective to rock the cam lever and cause it to disconnect the detent from the line-space wheel while the platen is being turned by the driving lever, means to return the driving lever to normal position, and a switch to hold the pawl in idle position.

8. In a typewriting machine, the combination with a platen having regular line-space mechanism including a toothed line-space wheel, and a detent therefor, of a pinion connected to turn with the platen, a multiplying gear in mesh with the pinion, a ratchet turning with the multiplying gear, the ratio existing between the teeth of the multiplying gear and the teeth of the pinion controlling the ratio between the teeth of the ratchet and the teeth of the line-space

wheel, and a driving mechanism including a pawl to engage the teeth of the ratchet to turn the platen through a comparatively long arc of movement by a comparatively short throw of the driving mechanism.

9. In a typewriting machine, the combination with a platen rotatable in a platen frame, and line-space mechanism including a line-space wheel, and a detent therefor, of a pinion connected to turn with the platen, a gear journaled on the platen frame and meshing with the pinion, a ratchet turning with the gear, a driving lever having a hub loosely journaled concentric with the axis of the gear, stops to arrest the throw of the driving lever in opposite directions, a pawl on the driving lever to engage the ratchet when the lever is swung in one direction, to turn the platen, an abutment projecting laterally from the pawl to strike one of said stops at a point near the platen frame at the end of the initial throw of the lever to prevent straining the stop, a switch engaged by the pawl on the return of the lever, to disengage the pawl from the ratchet and hold it ineffective, to enable the platen to be rotated in either direction independently thereof, a cam on the hub of the driving lever, a pivotally supported cam lever, one end of which is operated by the cam hub to rock the other end of the lever to release the detent from the wheel and hold it ineffective during the initial stroke of the finger lever.

10. In a typewriting machine, the combination with a rotatable platen, line-space mechanism including a line-space wheel to turn the platen, and a detent for the line-space wheel, of a driver or crank to turn the platen more than a line-space and throw the detent to inoperative position.

11. In a typewriting machine, the combination with a rotatable platen, line-space mechanism including a line-space wheel to turn the platen, and a detent for the line-space wheel, of a driver or crank to turn the platen and throw the detent to inoperative position, a ratchet turned by the crank, and gearing interposed between and connecting the ratchet and platen to transmit the motion of the crank thereto.

12. In a typewriting machine, the combination with a platen having a regular line-space mechanism, of an auxiliary mechanism including a driving lever, the initial throw of which in one direction causes a spring pressed pawl carried thereby to engage a ratchet to turn a gear in mesh with a pinion turning with the platen until the lever is arrested by a stop, a cam on the driving lever operating to rock a cam lever to disengage a detent from the line-space wheel while the platen is being turned, said lever being returned to original position, the pawl riding idly over the ratchet and

finally being shifted out of contact therewith by a switch to enable the platen to be turned in either direction independently of said auxiliary mechanism.

- 5 13. In a typewriting machine provided with a platen and a line-spacing mechanism, including a line-space wheel and a spring detent therefor, the combination of a lever, means connected to said lever for advancing the platen at one stroke through many line-spaces, and means controlled by said lever for releasing said detent from said line-space wheel.
- 10 14. In a typewriting machine provided with a platen and a line-spacing mechanism, including a line-space wheel and a spring detent therefor, the combination of a lever, means connected to said lever for advancing the platen at one stroke through many line-spaces, means controlled by said lever for releasing said detent from said line-space wheel, said releasing means including a cam connected to said lever, and a connection from said cam to said detent.
- 15 15. In a typewriting machine provided with a platen and a line-spacing mechanism, including a line-space wheel and a spring detent therefor, the combination of a lever, means connected to said lever for advancing the platen at one stroke through many line-spaces, said lever having a cam, and means controlled by said cam for releasing said detent from said line-space wheel, said cam provided with a dwell portion to hold the detent out of use during the operation of the lever.
- 20 16. In a typewriting machine provided with a platen and a line-spacing mechanism, including a line-space wheel and a spring detent therefor, the combination of a lever, means connected to said lever for advancing the platen at one stroke through many line-spaces, means controlled by said lever for releasing said detent from said line-space wheel, said releasing means including a cam connected to said lever, and a lever intervening between said cam and said detent to be operated by the former to release the latter.
- 25 17. In a typewriting machine, the combination with a rotatable platen, a line-space mechanism including a line-space wheel to turn the platen, and a detent for the line-space wheel, of a driver or crank to turn the platen at one stroke through many line

spaces, and concomitantly throw said detent to an inoperative position.

18. In a typewriting machine, the combination with a rotatable platen, of a line-space mechanism for said platen, a detent for said platen, and a line-space mechanism supplementing said first-mentioned line-space mechanism, and acting by a single stroke to concomitantly throw said platen at least one "full line-space, and render said detent ineffective.

19. In a typewriting machine, the combination with a rotatable platen, of a line-space mechanism for said platen, a second line-space mechanism for said platen, a detent for said platen detached from and capable of movement independent of said second-mentioned line-space mechanism, said second-mentioned line-space mechanism acting to concomitantly turn said platen and render said detent ineffective.

20. In a typewriting machine, the combination with a platen, of a normal line-space mechanism for said platen, an extraordinary line-space mechanism for said platen, including a toothed wheel connected to rotate said platen, a lever and a pawl mounted on said lever arranged to engage said wheel to rotate said platen, a detent for said platen normally free from and acting independent of said lever when said lever is inactive, and cam means brought in play at the actuation of said lever, to force said detent to an ineffective or silent position.

21. In a typewriting machine, the combination with a platen, of a normal line-space mechanism for said platen, an extraordinary line-space mechanism for said platen, including a toothed wheel connected to rotate said platen, a lever, a pawl mounted on said lever arranged to engage said wheel to rotate said platen, and a switch for holding said pawl out of engagement with said wheel when said lever is in its inactive position, a detent for said platen normally free from and acting independent of said lever when said lever is inactive, and cam means brought in play at the actuation of said lever to force said detent to an ineffective or silent position.
